UNITED STATES PATENT OFFICE.

KAREL WILLEM GERARD JOHAN STOFFELS AND JOHANNES JACOBUS HENDRIKUS WILHELMUS WEELEN, OF AMSTERDAM, NETHERLANDS, ASSIGNEES TO NAAMLOOZE VENNOOTSCHAP INTERNATIONALE ELECTRICITEIT MAATSCHAPPIJ, OF AMSTERDAM, NETHERLANDS.

ELECTRICALLY-CONTROLLED SWITCH-OPERATING MECHANISM FOR RAILWAYS.

No. 887,980.

Specification of Letters Patent.

Patented May 19, 1908.

Application filed January 23, 1907. Serial No. 353,742.

To all whom it may concern:

Be it known that we, KAREL WILLEM GERARD JOHAN STOFFELS and JOHANNES JACOBUS HENDRIKUS WILHELMUS WEELEN, subjects of the Queen of the Netherlands, residing at Amsterdam, Netherlands, have invented new and useful Improvements in Electrically-Controlled Switch-Operating Mechanism for Railways, (Stoffels's system,) of which the following is a specification.

This invention relates to an electrically-controlled switch-operating mechanism for railways, "Stoffels' system", which essentially comprises a box fixed in the ground and containing two wire coils, a specially constructed relay for making and breaking the circuit for the said coils and a contact device suspended in the overhead or trolley wire of the tramway network or system.

Having briefly outlined our improved construction, we will proceed to describe the same in detail, reference being made to the accompanying drawing, of which

Figure 1 is a diagrammatical complete view of the electrically-controlled switch-operating mechanism; Figs. 2 and 3 are side elevations of the contact pieces provided on the trolley wire; Fig. 4 is a section on line A—B of Fig. 2 and Fig. 5 is a section on line C—D of Fig. 3.

There are arranged in a box fixed in the ground two coils B C wound with wire, the coil B having thicker windings than C. There is fixed within each of the coils in the said box an iron core; these cores are attached to a lever which is connected with the switch-tongue. According as current passes through either coil, one of the cores is drawn inside the coil and consequently the switch tongue is shifted for either direction.

The relay employed for the present arrangement is of the following construction:—a b c and d are contact blocks, e is a contact spring, g and f are contact pieces, which are insulated by non-conducting material i. h is an iron core, which can be lifted from the coil A and thus raises the lever arm k, which turns on the fulcrum m and thereby lowers the contact piece f. l is a piece of insulating material and k is permanently connected with the overhead wire.

The contact device comprises two contact pieces insulated from each other and from

the overhead wire. One contact piece is longer than the other so that when the car runs on the track in the direction of the arrow, only one contact piece lifts the collector of the motor car from the overhead wire and then both contact pieces perform the same together and are finally connected by the collector. The longer of the two contact pieces is connected to one end of the coil A and the other one to the contact block c.

The operation is as follows: If a car approaches the contacts of the overhead wire and the motorman has not turned on the current through the medium of the controller, the relay remains in a position of rest when the collector comes in contact with the contact piece n because no connection from n is established and neither with the overhead wire or the positive pole, nor with the rail or the negative pole. If however the car, in consequence of its *vis viva*, runs further beneath the contact o, the current passes from the overhead wire over k, g, b, A, n, the sliding piece of the trolley, over o c e and through the coil C to the rail. By the insertion of a resistance w, the current intensity is regulated to such an extent that the flow of current is sufficient to actuate coil c but not sufficient to render coil A operative. The switch-tongue is thus shifted for one direction of travel. Now if the contact n is traversed while the motorman has turned on the current, the entire current of the car will pass from the overhead wire through k, g, b, coil A to n and through the car to earth. This current is of sufficient strength to render the coil A operative; it lifts h and as g thus bears against a and f against d, e being simultaneously separated from c, the current of the car now passes from the positive wire to k, g, a through the coil B to f, d, through A to n and through the car to earth. The coil B will thus be connected with coil A in series and the entire current of the car will flow through the same. Coil B attracts its core so that the switch tongue is shifted. The contact o is simultaneously rendered inoperative, as the spring contact e has been separated from c. As g bears against a and f against d before g is separated from b, a "break" spark will never be produced on the relay.

Having now particularly described and

ascertained the nature of our said invention and in what manner the same is to be performed, we declare that what we claim and wish to secure by Letters Patent is:—

- 5   In an electrically - controlled point or switch-operating mechanism for railways consisting of solenoids fixed in the ground and controlling the switch with their cores, of a relay for making and breaking the circuit for the coils and of a contact device suspended to the overhead wire of the tramway network or system, said relay comprising the contact blocks (*a b c d*), a contact spring (*e*), a lever (*k*), contact pieces (*g f*) attached to the lever (*k*) and insulated from each other by non-conducting material (*i*) and a core (*h*) adapted to be influenced by the coil (*A*) which, when attracted by the latter, turns the lever (*k*), that is insulated from the con-

tact piece (*c*) and connected to the overhead 20 wire, on its fulcrum (*m*) in such a manner that the contact piece (*f*) comes in contact with the contact piece (*d*), whereby the coil (B) is energized and traversed by the entire current of the car in the known manner, the 25 switch-tongue being shifted owing to the core of the said coil having been drawn inside, substantially as described.

In testimony whereof we have signed our names to this specification in the presence of 30 two subscribing witnesses.
